UNITED STATES PATENT OFFICE.

CLIFTON W. SHERMAN, OF BUFFALO, NEW YORK

DRAFT-GEAR.

1,202,907.

Specification of Letters Patent. Patented Oct. 31, 1916.

Application filed July 21, 1914. Serial No. 552,172.

To all whom it may concern:

Be it known that I, CLIFTON W. SHERMAN, a citizen of the United States, residing at Buffalo, in the county of Erie and State of New York, have invented new and useful Improvements in Draft-Gears, of which the following is a specification.

This invention relates to a friction draft gear or shock absorbing mechanism which is 10 more particularly designed for use in railway cars for the purpose of relieving the frame or body of the car from undue shock or strain during the buffing operation when coupling the cars and during the pulling operation while drawing the cars.

It is the purpose of this invention to provide a draft gear of this character in which the number of parts is reduced so as to make the same more compact and capable of being 20 produced at less cost without reducing the strength or sacrificing any of the cushioning or shock absorbing capacity of the gear.

In the accompanying drawings: Figure 1 is a vertical longitudinal section of my improved friction draft gear taken in line 1--1, Fig. 2. Fig. 2 is a horizontal section taken in line 2--2, Fig. 1. Fig. 3 is a vertical transverse section taken in line 3--3, Fig. 2.

Similar characters of reference indicate 30 corresponding parts throughout the several views.

Although the body or frame of the car which is adapted to receive my improved friction draft gear may be variously constructed that shown in the drawings is suitable and comprises two longitudinal draft sills 1, 1 preferably constructed of channel iron, front cross pieces 2, 3 connecting the front parts of the sills and a rear cross piece 4 connecting the rear parts of these sills.

5 represents the head of the car coupler which is arranged at the front end of the car and provided with a longitudinal shank 6 projecting rearwardly from the head and arranged between the front parts of the car sills.

The inner opposing sides of the car sills are provided with cheek plates or reinforcing bars 7 which are preferably constructed of cast steel and secured to the adjacent parts of the sills by means of rivets 8, as shown, or other suitable means. In the front ends of these cheek plates and the adjacent parts of the sills these members 55 are provided with coinciding front longitudinal slots 9. At the rear ends of the

cheek plates and the adjacent parts of the sills longitudinal slots 10 are formed, and in the central parts of these cheek plates and the adjacent parts of the sills are formed 60 intermediate longitudinal slots 11, each of these slots being formed partly in one of the cheek plates and the companion car sill.

12 represents a friction member which preferably has the form of a cylinder and is 65 arranged between the rear parts of the cheek plates.

Projecting forwardly from horizontally opposite sides of the front end of the friction cylinder are two draft arms or bars 13 each of which is provided at its front end with a longitudinal slot 14 and at its rear end adjacent to the front end of the friction cylinder with an intermediate longitudinal slot 15. At its rear end the friction cylinder is 70 provided on its horizontally opposite sides with two rearwardly projecting draft arms or lugs 16 each of which is provided with a rear longitudinal slot 17. This friction cylinder and its front and rear draft arms are 75 preferably formed integrally of cast steel.

18 represents a front follower which is arranged between the front draft arms in rear of the coupler shank and which is preferably constructed of cast steel in the form of a block and provided with a longitudinal slot or opening 19 which extends transversely from side to side thereof.

20 represents a rear follower which is arranged between the rear draft arms and which is preferably constructed of cast steel in the form of a block and provided with a longitudinal slot or opening 21 extending transversely from side to side of this follower.

The rear or inner ends of the cheek plates 7 are provided with forwardly facing shoulders 40 which are adapted to be engaged by the draft lugs 16 of the friction cylinder and the rear follower 20 in the rearmost position of these parts, as shown in Fig. 2.

22 represents a front key having, preferably, the form of a flat plate which extends transversely through a slot 23 in the rear part of the coupler shank and through the front slots 14, of the front draft arms, and slots in the cheek plates and sills. This front key is as wide as the longitudinal slot or opening in the coupler shank so that the front and rear edges of this key at the central part thereof engage with the front and rear ends of the slot in the coupler shank

and these parts are compelled to move forwardly and backwardly together. These portions of the front key extending through the front slots of the front draft arms are of less width than the length of said slots so that this key and the front draft arms, at times, are free to move independently of each other in a direction lengthwise of the car. The slots 9 in the front parts of the cheek plates and the sills are of such a length as compared with the width of those portions of the front key arranged in the same that this key is always free to move forwardly and backwardly on the cheek plates and sills either while the friction gear is subjected to buffing strains or pulling strains. Under normal conditions this key does not engage either the front or the rear ends of the front slots in the cheek plates and sills but merely slides therein for the purpose of supporting and guiding the coupler shank, the front draft arms and the parts associated therewith.

25 represents an intermediate key also preferably constructed in the form of a flat plate which extends through the slot or opening of the front follower, the intermediate slots 15 of the front draft arms and the intermediate slots 11 of the cheek plates and sills. The width of this key in the direction of the length of the car is less than the length of the slot in the front follower and the intermediate slots in the front draft arms and the cheek plates and sills.

26 represents a rear key constructed preferably in the form of a flat plate and extending transversely through the slot or opening of the rear follower, the slots 17 of the rear draft arms and the rear slots 10 of the cheek plates and sills. The length of the slot or opening in the rear follower is equal to the width of the rear key so that the latter and the rear follower always move together and the slots of the rear draft arms are also equal to the width of the rear key so that this key fits snugly in the rear follower and rear draft arms and these parts are compelled to move together in the direction of the length of the car. The rear slots 10 in the cheek plates and sills are of a length greater than the width of the rear key passing through the same so that this key at times is free to move lengthwise in these slots. Each of the keys is confined against lateral displacement by means of retaining pins 24 or similar fastenings extending vertically through openings in opposite ends of this key and engaging in outer sides of the sills, as shown in Figs. 2 and 3.

27 Within the rear part of the friction cylinder and engaging with the front side of the rear follower is a yielding member or spring element which preferably comprises an outer heavy spring section 27 and a light inner spring section 28 arranged within the outer

spring section both of these spring sections being preferably constructed in the form of coils. Within the front end of the friction cylinder and between the rear side of the front follower and the front end of the spring 27, 28 is arranged a wedging device whereby the bore of the friction cylinder is engaged for the purpose of obtaining frictional resistance in addition to the spring resistance of said spring both during the 75 buffing and pulling operations of the car. This friction device preferably comprises a plurality of sets of friction shoes and wedges, said wedges and said sets of shoes, being arranged alternately and in tandem 80 within the front part of the friction cylinder. In the preferred organization of this wedging device the same comprises a set of rear friction shoes 29 which engage their outer sides with the bore of the cylinder and 85 their rear ends with the front end of the spring element, a rearwardly tapering wedge 30 arranged within the cylinder in front of the rear set of shoes and engaging its inclined faces with correspondingly inclined 90 faces 31 on the front ends of the rear shoes, a set of front friction shoes 32 engaging their outer sides with the bore of the cylinder while their transverse rear ends engage with the transverse front end of the 95 rear wedge, and a front wedge 34 having a transverse front face which engages with the transverse rear face of the front follower and having its rearwardly inclined or converging faces engaging with correspondingly inclined faces 36 at the front ends of the front set of friction shoes, as shown in Fig. 2.

In the normal inoperative position of the parts of the friction draft gear the front 105 key 22 engages with the front ends of the front slots 14 in the front draft arms while the opposite ends of this key are arranged in the central parts of the slots 9 in the cheek plates and sills, the intermediate key 110 25 engages with the rear end of the slot in the front follower and with the front ends of the intermediate slots 15, 11 in the front draft arms, and the cheek plates and sills, the rear key 26 engages with the rear ends 115 of the rear slots 10 in the cheek plates and sills, and the draft arms 16 and rear follower 20 engage with the rear shoulders 40, as shown in Fig. 2. When the coupler is pushed rearwardly during a buffing action, 120 such as occurs when coupling two cars, the friction cylinder is held against backward movement by reason of the rear key 26 abutting against the rear ends of the rear slots 10 in the cheek plates and sills and the 125 draft arms 16 and rear follower 20 abutting against the shoulders 40 while the front key 22 slides rearwardly in the front slots 9 of the cheek plates and sills, and the front follower slides rearwardly on the intermediate 130

key. During this movement of the coupler and front follower the front and rear wedges by their wedging engagement with the front and rear set of friction shoes cause the latter to be pressed outwardly into frictional engagement with the bore of the friction cylinder so as to frictionally resist the buffing action and as the rear set of shoes moves rearwardly the spring 27, 28 is compressed and resists the buffing strains, the combination of these two resistances operating to cushion the buffing blow when coupling two cars. While the car is being pulled the front key by engagement with the front ends of the front slots 14 in the front draft arms causes the cylinder and the rear key and rear follower connected therewith to be drawn forwardly while the front follower remains at rest by reason of the rear end of its slot 19 abutting against the rear edge of the intermediate key 25 and the front edge of this key abutting against the front ends of the intermediate slots 15 in the cheek plates and sills, during which time the two sets of brake shoes are pressed outwardly into frictional engagement with the bore of the friction cylinder by the wedging action against the same of the wedges and the spring 27, 28 is compressed between the rear set of friction shoes and the rear follower, whereby the pulling strains are cushioned and the shock attending the same is absorbed.

As shown in Fig. 2, the angle of wedging engagement between the rear wedge and the rear set of shoes which are nearest to the spring is more acute than the angle of wedging engagement between the front wedge and the front set of shoes which are farther removed from the spring, thereby causing the amount of frictional shock absorbed by the near set of shoes to be relatively increased, and the amount of shock absorbed by the remoter set to be relatively diminished, and the amount of frictional shock absorbed by the several sets of shoes to be substantially equalized owing to the progressive increase in the acuteness of the wedging angle between successive sets of contacting wedges and shoes toward the spring. Furthermore, the frictional bearing surfaces of the rear set of shoes against the bore of

the cylinder is smaller than the frictional bearing surface of the front set of shoes against the same, whereby the frictional bearing surfaces of the several sets of shoes is successively increased in area away from the spring and the amount of frictional shock absorbed and the intensity of pressure against the frictional surfaces is substantially equalized.

In the construction of this friction draft gear the usual friction cylinder and draft yoke which have heretofore commonly been made as separate members are in the present construction so organized that but one part or member practically performs the function of two of such members made separately, thereby not only reducing the cost of manufacture but also economizing in the amount of space used and also producing a much stronger and durable construction than the friction gears heretofore in use as well as reducing the liability of breakage and the repairs incident thereto.

I claim as my invention:

A friction draft gear comprising longitudinal sills having front intermediate and rear longitudinal slots, a friction cylinder arranged between said sills and having front and rear draft arms, said front arms having front and intermediate longitudinal slots and said rear arms having rear longitudinal slots, a coupler having a shank provided with an opening, a key immovable lengthwise in the opening of said shank and movable lengthwise in the front slots of said front arms and sills, a front follower having a longitudinal slot, a key movable lengthwise in the slot of said front follower and the intermediate slots of said front arms and the sills, a rear follower provided with an opening, a key immovable lengthwise in the openings of said rear follower and said rear arms and movable lengthwise in the rear slots of said sills, and cushioning means interposed between said front and rear followers.

Witness my hand this 13th day of July, 1914.

CLIFTON W. SHERMAN.
